Specification for Design.

Patented July 29, 1913.

Application filed March 17, 1913. Serial No. 755,039. Term of patent 3½ years.

To all whom it may concern:

Be it known that I, JOHN F. B. FERRY, a citizen of the United States, residing in the city and county of San Francisco, State of California, have invented a new, original, and ornamental Design for a Badge, Pin, or Similar Article, of which the following is a specification, reference being had to the accompanying drawing, forming part thereof, wherein the figure is a view in elevation of a pin-head, showing my new design.

I claim:—

The ornamental design for a badge, pin or similar article, as shown.

In witness whereof I have signed my name to this specification in the presence of two witnesses.

JOHN F. B. FERRY.

Witnesses:

HARRY A. TOTTEN,
